Design for the Statue and Clock

By William H. Gild

Patented April 2, 1866

Chicago, Ill.

DES. 2290

William A. Giles, of Chicago, Ill.
Letters Patent No 2290, Dated April 3, 1866,
Design for a Statuette and Clock case.

The schedule referred to in these Letters Patent and making part of the same.

To all whom it may concern:

Be it known that I, William A. Giles, of Chicago in the County of Cook, and State of Illinois, have invented or produced a new and original design for a Statue or Statuette and Clock, and I hereby declare that the following is a full and exact description of the same.

In the centre of the design is a full length statue or statuette of President Lincoln seated in a chair, holding in one hand the Emancipation Proclamation and in the other the pen with which he has just finished writing. The hand holding the pen rests upon his knee, his other arm leans slightly upon a circular block base standing by his side. His head is turned slightly to one side and his face is full of earnest thought as if he were meditating upon the consequences of the measure he is about to adopt.

The front of the block base is ornamented with stars running all around the face; below the base are two flags, one on each side; the flag staffs pointing outwards and upwards, a shield between them and all three, the shield and the flags bearing the stars and stripes.

Lying on the ground between the feet of Lincoln and the flag and partly covered by the latter is a large book.

On one side of the design and half concealed among leaves and flowers is a dismounted canon and one of the wheels.

2

DES. 2290

This design is supported upon a pedestal long and low and resting upon four small feet one at each corner. It is intended chiefly for a mural ornament, and to be made of bronze, but may be made of any other suitable material and used in any other suitable way.

Having thus described my design, what I claim as my invention or production, and desire to secure by Letters Patent is

The design for a Mantle Ornament "composed of a Block base and Statuette combined substantially as shown and described."

Witness,

Geo. Payson
Chas. W. Gregory

W. A. Gibbs
